UNITED STATES PATENT OFFICE

2,106,605

DISTURBANCE RESPONSIVE SWITCH

Frederick B. Johnson and Irvin Jacobson, Kansas
City, Mo.

Application November 8, 1934, Serial No. 752,008

7 Claims. (Cl. 200—52)

This invention relates to a disturbance responsive switch adapted to be actuated incidental to movement of an object carrying the switch, for example, a motor vehicle, and has for its principal object to provide a device of this character that is sensitive to the slightest movement of the vehicle in any direction, but which is in no way affected by an angular condition of the vehicle as long as it is in a state of rest.

10 In accomplishing these and other objects of the invention, as hereinafter set forth, we have provided improved details of structure, the preferred form of which is illustrated in the accompanying drawing, wherein:

15 Fig. 1 is a perspective view of a portion of a motor vehicle equipped with a theft alarm including a disturbance responsive switch embodying the features of the present invention.

Fig. 2 is an elevational view of the alarm partly 20 in section to better illustrate the construction and support of the contact elements of the switch.

Fig. 3 is an enlarged horizontal section on the line 3—3, Fig. 2.

Fig. 4 is a vertical section through the disturbance responsive switch contact assembly.

Fig. 5 is a detail perspective view of the circuit interrupting switch and lever for rendering the disturbance responsive switch ineffective.

Fig. 6 is an enlarged elevational view of the 30 switch mechanism for controlling the time period within which the signal is active after being actuated by the disturbance responsive switch.

Fig. 7 is a diagrammatic view of alarm circuit in which the disturbance responsive switch is 35 connected.

Referring more in detail to the drawing:

1 designates a disturbance responsive switch and associated mechanism including a frame 2 having vertical leg portions 3 and 4 connected at 40 their upper ends by a cross bar 5 provided with vertical side flanges 6 and 7 to suspend the frame from a clamping device 8.

The clamping device illustrated includes a block 9 having a transverse V-shaped groove 10 in one 45 face thereof cooperating with a clamping plate 11 to engage a part of the object on which the switch is to be mounted as, for example, a brace rod 12 connecting the radiator (not shown) with the dash 13 of a motor vehicle designated 14. The 50 plate 11 is secured in clamping engagement with the rod by fastening devices such as screws 15 extending through the plate and threaded into the block as best illustrated in Fig. 1. The lower end of the block 9 engages between the flanges 55 and 6 of the frame 2 and is secured thereto by a

bolt or the like 16 extending through the flanges and through the depending end of the block.

The lower ends of the leg portions 3 and 4 of the frame are connected in spaced relation by a cross bar 17 that is attached to a base plate 18 5 preferably formed of insulating material to mount an alarm element later described.

Formed on the frame substantially midway of the height of the legs 3 and 4 and projecting inwardly thereof are aligning bosses 19 and 20 having threaded sockets 21 and 22 for adjustably mounting screws 25. The inner end of the boss 19 and the trunnion screw 25 in the boss 20 carry trunnion points 27 and 28 for pivotally mounting a gimbal ring 29 which in turn pivotally mounts 15 a pendulum housing 30.

The pendulum housing 30 includes upper and lower sections 31 and 32 connected by an intermediate coupling ring section 33. The upper section is of smaller diameter than the inner diameter of the gimbal ring to provide free swinging movement of the housing within the ring in a direction transversely to the axis of the trunnion points previously described, so that the housing is universally suspended within the frame to retain 25 a perpendicular position regardless of the angularity of the frame or support on which the frame is mounted.

The upper end of the section 31 has diametrically opposed trunnion openings 34 and 35 for 30 accommodating the trunnion points 36 and 37 on screws 38 and 39 that are adjustably threaded through the gimbal ring at right angles to the axis of the trunnion points 27 and 28. The upper end of the section 31 is closed by a disk 40 preferably formed of insulating material to mount a contact element 41 later described.

The opposite end of the housing section 31 is internally threaded to engage the upper threaded end 42 of the coupling ring 33 and is normally prevented from relative rotation therewith by a lock ring 43 that is also threaded on the coupling member and is moved in abutting engagement with the lower end of the upper housing section. The lower end of the coupling member 45 is provided with an annular collar 44 forming an end abutment for the upper end of the lower housing section which is threaded thereon as illustrated in Fig. 2 to complete the housing for the fixed and pendulum contact elements 41 50 and 45 to close the signal circuit as now to be described.

The fixed contact element 41 includes a bushing 46 that is mounted in an opening 47 of the insulating disk 40 and is provided with an inter- 55

nally threaded bore 48 to adjustably mount the threaded shank 49 of a contact head 50. The contact head 50 is preferably of disk shape having a flat contact plate 51 to cooperate with a similar plate 52 of the pendulum contact element 45. The pendulum contact element includes a cylindrical body 53 carrying the contact 52 and is provided with a transverse bore 54 for projection therethrough of a transverse fulcrum bar 55 that has its ends mounted in slots 56 and 57 provided in the coupling ring 33 as best illustrated in Fig. 4, the ends of the bar being retained in seated condition in the slots by fastening devices 58 extending through the ends of the bar and threadedly engaged in sockets in the bottom of the slots.

Threadedly mounted in the body portion of the pendulum and projecting into the transverse bore is a fulcrum screw 59 having a cone-shaped point 60 on its lower end engaging a socket 61 in the top of the bar. Formed on the lower end of the body portion of the pendulum is a threaded stud 62 for supporting a weight 63.

It is thus apparent that the pendulum is fulcrumed on the bar to normally retain the contact plate 51 thereof in parallel spaced relation with the contact plate 51 on the fixed element to normally break the circuit therebetween, but the pendulum is free to swing in all directions incidental to its point support on the bar 55 to cause the peripheral edge of the contact face 52 to engage the contact plate 51 of the fixed element. If the housing is moved from perpendicular position in any direction, the pendulum remains stationary and the fixed contact 51 engages with the peripheral edge of the pendulum contact 52 to close a circuit therethrough.

In order to retain the fulcrum screw in engagement with its socket and limit upward movement of the pendulum under vibration, the stud 62 is provided with an internally threaded bore to accommodate a screw 64 having a cone shaped upper end 65 slightly spaced from the bottom and a cone shaped recess 66 formed in the lower side of the transverse bar 55, the spacing between the screw and socket being sufficient to allow the maximum swinging movement of the pendulum.

To lock the fixed contact element 41 in adjusted position relatively to the contact plate 52 of the pendulum 45, the bushing 46 is provided with a set screw 67 engaging the threaded shank 48 of the contact element.

In order to provide a sufficient weight in the housing to retain the housing in perpendicular position, the lower section is provided with an annular collar 69 of considerable weight and which is preferably knurled to permit adjustment of the coupling section relatively to the housing, thereby varying the relative spacing between the contact faces.

The lower contact plate is directly grounded on the frame through a flexible connection 70 fixed to the contact 45 and to the coupling ring 33 of the housing as best shown in Fig. 4. The fixed contact element is connected by a conductor 71 leading to a relay switch designated 72 carried by the frame 2 and adapted to close a circuit leading to a source of current supply to retain the signal in operation after the circuit has been broken through separation of the contact plates 51 and 52.

The relay switch 72 includes a pivoted arm 73 carried by the frame 2 in alignment with the core of the solenoid and having interconnected contacts 74 and 75 adapted to engage a fixed contact

76 that is connected with the alarm element such as a bell 77 and a lamp 78 by a conductor 79 and a fixed contact 80 that is connected to a contact 81 of a secondary switch 82 through a conductor 83.

The relay switch also includes a solenoid 84 provided with a winding 85 having one terminal connected to the movable contact 86 of the secondary switch 82 and having its other terminal connected to a source of current supply such as a battery 87 by means of a conductor 88.

It is thus apparent that when the device is vibrated to cause either the pendulum weight 63 or the housing to swing, the peripheral edges of the contacts 51 and 52 will engage each other to close circuit through the battery 87, conductor 88, solenoid winding 85, secondary switch 82, contacts 51 and 52 and conductor 70 to the ground and back to the battery.

This flow of current energizes the solenoid 84 and effects actuation of the arm 73 to close the contacts 74-80 and 75-76 causing the current to flow through the secondary switch 82 and to the signal circuit to energize the bell 77 and light the lamp signal 78, thereby giving warning that the vehicle has been moved from its state of rest.

With the circuit thus far described, it is apparent that as long as current is flowing through the solenoid, the relay contacts will remain closed to continue operation of the signals.

It is, therefore desirable to provide means for automatically breaking the circuit to the relay after the signal has been energized and to accomplish this, we provide for thermostatic operation of the secondary switch 82.

The movable contact 86 for the secondary switch is mounted on a spring leaf 89 to be normally retained thereby in contact with its complementary contact 81. 90 designates a thermostat element preferably formed of metal and having one end thereof fixed to a bracket 91 and its opposite end normally engaging a lug 92 on the contact spring 89. Coiled about the thermostat is a heating element 93 having one lead connected to the conductor leading to the secondary contact switch 86 and the other to the conductor 88. Upon flow of current through the solenoid, a portion of the current will be shunted through the resistance 93 to heat the thermostat element 90 which is set so that after the temperature has reached a given point the thermostat element will flex to raise the spring contact 86 of the secondary switch, thereby breaking circuit to the solenoid which in turn interrupts the current supply to the bell 77 and lamp 78 through the contacts 76 and 80.

When current has broken through the solenoid 84, the current is also broken through the heating element by the secondary switch 82 and this switch will not close until the resistance element 90 has cooled sufficiently to allow closure thereof. The circuit will not again be energized unless the vehicle is again moved to cause swinging of the pendulum to energize the circuit as previously described. In order to set the timing between the make and break of the secondary switch by means of the thermostatic element, the thermostatic element is mounted on a pivoted lever 94 that is pivoted on the bracket 91 and is engaged by set screws 95 and 96 that are threaded through the fixed bracket 91 and which have their ends engaging against stop shoulders on the lever 94 at opposite sides of the lever pivot.

It is thus apparent that by tightening one

screw and slackening off the other, the thermostatic element may be tensioned so that it will be caused to break the circuit through the secondary switch at selective time periods.

5 In order to prevent energization of the circuit when the vehicle is in use by an authorized person, a manually operated switch 97 is connected in the conductor 88. This switch 97 includes a contact clip 98 that is fixed to a plate 99 carried 10 on the insulating plate 18 adjacent the lower end of the contact housing. Pivoted to the lower end of the leg 4 of the frame 2 is a lever 100 operating through a slot 101 in the leg 4 and extending under the weight 62 so that its opposite end 102 is 15 operable through an opening 103 in the lower end of the leg 3. The projecting end of the lever is connected by a flexible cable 104 to an operating button on the dash of the vehicle. Directly under the pendulum weight 64 is an inverted cone-shaped plate 105 having a tongue 106 thereon pivotally mounted in a slot 107 in the collar of the lower housing section so that the center thereof is supported in contact with a lug 108 provided 20 on the upper face of the lever 100. Formed on the lever 100 on the side adjacent the clip 98 is a laterally extending arm 109 having a contact 110 to engage the clip.

It is thus obvious that when the flexible connection 104 is moved to raise the lever arm 100, 30 the contact 110 will be moved from engagement with the clip 98 and the lug 108 thereon will be moved against the pivoted disk to engage against the pendulum weight 64 and prevent swinging thereof that might cause damage to its fulcrum 35 including the fulcrum screw 59.

It is also desirable to provide the conductor wire with a second switch 111, preferably of the permutation type, that is mounted exteriorly of the vehicle as shown in Fig. 1 and which is connected in circuit with the conductor by wires 112 and 113 so that the circuit may be closed after the operator has closed the switch 97 and locked the doors of the vehicle.

The bell 77 and signal 78 may be located on any 45 convenient part of the vehicle. We prefer, however, to mount the bell directly on the lower face of the insulated plate 18 and the lamp 78 on the instrument board of the vehicle.

As an added precaution, switches as indicated 50 at 114 may be connected into the circuit to cause energization of the alarm. One of these switches is preferably located so as to be operated in case some one should attempt to raise the hood without effecting movement of the vehicle.

55 While we have specifically referred to the audible signalling device or alarm as a bell, it is obvious that a horn, buzzer, or other similar device may be substituted, or the horn which is the standard equipment of the vehicle may be connected into the circuit in lieu of the independent sounding device.

In operating a mechanism constructed and mounted on a motor vehicle as described, and assuming that the vehicle is being operated by an 60 authorized person, the pendulum weight 62 is engaged by the lug 108 on the lever to hold the point of the screw 64 in engagement with the socket 66 to prevent swinging of the pendulum.

When the driver wishes to park the car, he will 65 operate the cable 104 to close the switch 97 and release the pendulum from contact with the lug 108. After leaving the car and locking the doors thereof, the permutation lock will be operated to close the permutation switch from the exterior 70 of the car, completing the setting of the alarm.

As long as the car is stationary, the contacts 51 and 52 will remain open regardless of the position of the car, due to the universal mounting of the housing. The pendulum will, therefore, hang in a perpendicular position to maintain spacing between the contacts 51 and 52. However, should an unauthorized person move some portion of the car to cause swinging of the housing of the pendulum the contacts will engage to close the circuit through the relay 10 switch 72, secondary switch 82, and ccw inductor 76 to the ground, energizing the relay switch to close the circuit to the bell 77 and lamp 78.

Current will also flow through the heating element to heat the thermostat. The bell will continue to ring until the thermostat has been heated sufficiently to cause separation of the contact 86 of the secondary switch. When this occurs, the circuit through the relay switch is interrupted which effects breaking of the circuit to 20 the bell 77 and lamp 78. The signal will not again be energized unless another attempt is made to enter the car. Upon cooling of the thermostat, the circuit will be reestablished through the secondary switch and should the 25 car be moved a second time, the contacts 51 and 52 will again close the circuit to again effect operation of the signals.

While the switch device may be mounted on any part of the car, it is readily energized through 30 any vibratory movement applied to any part of the car, such as the tires, spare wheel, or other accessories. The signal alarm will, therefore, not only protect the car against theft, but will also protect the car against loss of the accessories, 35 since an attempt to remove the accessories will cause movement of the car to energize the signal.

If desired, the gimbal ring may be dispensed with and the housing 30 can be universally suspended by means of a pivot pin and bar similar 40 to the suspension means for the pendulum as above described.

What we claim and desire to secure by Letters Patent is:

1. In a device of the character described, a 45 housing, a pair of facing disk-like contacts having substantially flat contact faces for controlling an electrical circuit, a pivotally mounted support in the housing for carrying one of the contacts with the contact face normally arranged in a horizontal plane, means for pivotally supporting the other contact on said pivotally mounted support with its contact face in a horizontal plane in normally spaced relation and in axial registry with the first named contact, and means for engaging one of the contact supports to selectively prevent movement of said supports, said contacts being movable in peripheral contacting relation with each other responsive to vibratory movement of said supports. 55

2. In a device of the character described, a pendulum, a disk-like contact carried by the pendulum having a normally horizontal contact face, means supporting the pendulum for oscillatory movement, means for swingingly suspending said supporting means, a similar contact having a contact face normally retained in a horizontal plane on said last named suspending means in vertically spaced facing relation with the first named contact and adapted to be engaged by the first named contact upon swinging movement of the pendulum, and means for selectively engaging the pendulum to prevent oscillatory movement thereof. 70

3. In a device of the character described, a 75

support, a gimbal ring pivotally mounted on the support, a pendulum housing swingingly mounted on said gimbal ring, a pendulum, means pivotally supporting the pendulum in the housing, 5 a flat disk-shaped contact carried on the pendulum above the pivotal support, and a similar contact carried by the housing in vertically spaced relation with the pendulum contact and adapted to be engaged by the pendulum contact 10 for closing a circuit incidental to relative movement of the housing and pendulum.

4. In an apparatus of the character described, a support, a contact carrying member, means pivotally suspending the contact carrying member 15 on the support whereby said contact carrying member retains perpendicularity during change of position of said support, a substantially disk-like contact carried by said member and having a downwardly facing normally horizontal contact face, a second contact carrying member, a contact on said second contact carrying member of similar shape and having a normally horizontal contact face, and means mounting said second contact carrying member 20 for oscillatory movement on the first contact carrying member with said contact faces in spaced facing relation whereby said last named contact is caused to peripherally engage the other contact upon oscillatory movement of the 25 second contact carrying member.

5. In an apparatus of the character described, a support, a pendulum housing, means universally suspending the pendulum housing on the support, a contact carried in the axis of the 35 housing and having a substantially flat horizontal contact face, a pendulum including a body having a transverse bore, a fulcrum bar supported by the housing and extending through said bore, a fulcrum member carried by the pendulum and having point bearing on the ful-

crum bar, and a contact carried by the body of the pendulum in normally spaced alignment with the first named contact and adapted to peripherally engage said contact upon relative movement of the pendulum in the housing. 5

6. In an apparatus of the character described, a support, a pendulum housing, means universally suspending the pendulum housing on the support, a contact carried in the axis of the housing and having a substantially flat horizontal contact face, a pendulum including a body having a transverse bore, a fulcrum bar supported by the housing and extending through said bore, a fulcrum member carried by the pendulum and having point bearing on the fulcrum bar, a contact carried by the body of the pendulum in normally spaced alignment with the first named contact and adapted to peripherally engage said contact upon relative movement of the pendulum in the housing, a stop member carried by the pendulum and engageable with the bar on the opposite side of said point bearing, and means for lifting the pendulum from said point bearing and the stop member into engagement with the fulcrum bar to selectively prevent said relative movement. 10 15 20 25

7. In a device of the character described, a support, a pendulum housing, means universally mounting the pendulum housing on the support, a pendulum, means universally mounting the 30 pendulum in the pendulum housing, contacts carried by the pendulum and housing for closing a signal circuit, a lever pivoted on the support, a pendulum engaging member pivoted in the housing, and means on the lever adapted to 35 engage said member to move the pendulum engaging member into contact with the pendulum to selectively prevent relative movement thereof.

FREDERICK B. JOHNSON.

IRVIN JACOBSON.
